UNITED STATES PATENT OFFICE.

ADOLPH W. WAERN, OF ONTONAGON, MICHIGAN.

PULP DIGESTER.

Application filed June 27, 1927. Serial No. 201,858.

This invention relates to pulp digesters.

In soda and sulphate pulp digesters, the digesting liquor is withdrawn from the bottom and pumped into the top of the digester.

5 The liquor may or may not be heated intermediate its withdrawal and recharging into the digester. When an outside circulating system for the liquor is used, a perforated false bottom is provided in the bottom or 10 lower end of the digester to prevent the pulp chips or undigested material from following the circulating liquor and clogging the pump or piping.

It is difficult in digesters having an inside 15 sloping false bottom to make a clean "blow" due to the fact that the wood chips, half or partly pulped are sucked against the false bottom and stick to the false bottom plates. As a result, a large quantity of the pulp does 20 not blow out and is left in the bottom of the digester. This condition, of course, very materially cuts down the efficiency of the digester since the capacity is decreased and unless the partly pulped chips are cleaned 25 out by a re-blow, practically all the pulp left over will be destroyed during the next cooking process.

Furthermore, in pulp digesters having the usual form of false bottom there is a large 30 dead space or waste space between the false bottom plates and the wall of the digester. This space contains no chips and thus reduces the capacity of the digester. Moreover, the space must be filled with liquor, 35 thus increasing the required quantity of liquor and the steam consumption required to heat the liquor.

With the above difficulties in mind, this 40 invention has for one of its objects to provide a pulp digester having a false bottom so constructed and arranged that the digester will be thoroughly cleaned out during the blow.

Another object of the invention is to provide 45 a construction of false bottom that will be easily accessible and can be readily removed, repaired and cleaned.

Another object of the invention is to provide 50 a false bottom for pulp digesters so constructed and arranged that the full capacity of the digester can be utilized for the charge.

Another object of the invention is to provide 55 a false bottom so designed that all dead space and the attendant evils will be eliminated.

Another object of the invention is to provide a false bottom so designed that the parts thereof cannot become loosened and injure the liquor circulating system.

Further objects of the invention will appear from the following specification taken in connection with the drawings, which form a part of this application, and in which

Fig. 1 is an elevational view of a digester and liquor circulating system constructed in accordance with the invention;

Fig. 2 is a sectional elevation of the lower end of the digester shown in Fig. 1;

Fig. 3 is a sectional elevation similar to Fig. 2 but showing a false bottom construction for digesters having a square bottom;

Fig. 4 is a sectional elevation of the screen utilized in the false bottom constructed in accordance with the invention; and

Fig. 5 is a top plan view of the construction shown in Fig. 4.

The invention briefly described consists of a pulp digester having a sloping lower end provided with a centrally disposed discharge outlet and a casing secured to the bottom of the digester around the discharge opening. The casing is preferably substantially cylindrical and a substantially cylindrical screen is mounted therein. The circulating liquor is withdrawn from the casing and is pumped back into the top of the digester. A bottom plate is secured to the lower end of the casing and is dished or downwardly inclined and has a discharge opening through which the digested pulp is discharged during the blow. Further details of the invention will appear from the following description.

The invention may be utilized with any type of pulp digester and in the drawings there is shown a digester 10 having a false bottom casing 11 secured to the lower end thereof, a pipe 12 secured to the false bottom casing and withdrawing the liquor therefrom by means of a pump 13. The pipe 12 is provided with a check valve 9 to prevent the pressure from the top of the digester reaching casing 11 through the circulating system. The pump discharges the liquor through a pipe 14 into a heater 15 which heats the liquor and the liquor is pumped from the heater through pipes 16 and 17 back into the top of the digester.

In the form of the invention illustrated in Figs. 1 and 2, the lower end 20 of the digester is tapered and is provided with a cen-

tral discharge opening 21. Steam nozzles 23 extend into the lower end 20 of the digester and conduct steam thereto from pipes 24.

The casing 11 is substantially cylindrical in shape and has a reduced upper end 25 provided with a flange 26 which is bolted or otherwise secured to the bottom of the digester 10 around the discharge opening 21.

A substantially cylindrical screen 30 is mounted in the casing 11 and has a flange 31 at the lower end secured between a bottom plate 32 and the lower end of the casing 11. The bottom plate and screen may be secured by bolts 33. The inner diameter of 15 the screen is substantially the same as the inner diameter of the reduced portion 25 of the casing 11 and as shown in Fig. 2, the upper end of the screen is disposed within an annular shoulder 34 formed between the 20 reduced portion of the casing and the remaining portion thereof. The screen, therefore, forms an annular chamber 35 in the casing.

The flange 31 of the screen is provided 25 with a plurality of conduits 38 which communicate with the annular chamber 35 and conduct thereto steam from steam pipes 39.

The bottom plate 32 of the casing 11 has 30 a central discharge opening 40 and has connected thereto a blow-out valve 41 connected to a blow pipe 42.

The construction shown in Fig. 3 is substantially the same as that illustrated in Figs. 1 and 2 except that the bottom 45 of the digester is square and a sloping bottom 46 is mounted within the bottom 45. The bottom 46 is not perforated but consists of plates supported on steel beams such as T-beams 47. The space between the supplemental bottom 46 and the square bottom 45 of the digester is preferably filled with concrete 48. This construction gives in effect the same results as those obtained by the sloping bottom 20 of the digester 10 shown 45 in Figs. 1 and 2 and the structure shown in Fig. 3 is merely illustrated to show how a square bottom digester can be changed or modified to adapt it for use with the improved false bottom device.

50 In the operation of the false bottom device, the digesting liquor is sucked through the screen 30 into the chamber 35 surrounding the screen and is pumped out of this chamber through the pipe 12. Since the 55 screen is substantially vertical, it will not become clogged and partially digested pulp chips will not be caused to adhere thereto by the suction of the circulating liquor. With this device, the digested pulp will be thoroughly cleaned out of the digester during the 60 blow. Furthermore, in case it becomes necessary to clean or repair the false bottom device, the entire device can be unbolted from the bottom of the digester and the parts 65 thereof will be readily accessible or by re-

moving the bottom plate 32, the screen can be vertically withdrawn from the casing, giving ready access to the parts to be cleaned or repaired.

With the present forms of false bottoms 70 it is necessary in order to clean or repair the parts for workmen to descend into the digester and to work therein. Moreover, although with the present forms of false bottom, parts become loose and cause damage 75 by being sucked into the circulating system, the nature of the design of the false bottom device above described eliminates loosening of parts or damage caused thereby.

Although certain specific embodiments of 80 the invention have been particularly shown and described, it will be understood that the invention is capable of modification and that changes in the construction and in the arrangement of the various cooperating parts 85 may be made without departing from the spirit or scope of the invention, as expressed in the following claims.

What I claim is:

1. A pulp digester having a discharge 90 opening at the lower end thereof, a casing secured to the bottom of the digester around the discharge opening, a screen in said casing and spaced from the walls thereof, and a liquor circulation suction conduit communicating with said casing, said casing having a discharge opening at the bottom thereof.

2. A pulp digester having a discharge opening at the lower end thereof, a casing secured to the bottom of the digester around the discharge opening, a substantially cylindrical screen in said casing and spaced from the walls thereof, and a liquor circulation suction conduit communicating with said casing, said casing having a discharge opening 100 at the bottom thereof.

3. A pulp digester having a discharge opening at the lower end thereof, a casing secured to the bottom of the digester around the discharge opening, an open-ended screen in said casing and spaced from the walls thereof, and a liquor circulation suction conduit communicating with said casing, said casing having a discharge opening at the 110 bottom thereof.

4. A pulp digester having a discharge opening at the lower end thereof, a casing secured to the bottom of the digester around the discharge opening, a substantially cylindrical, open-ended screen in said casing and spaced from the walls thereof, and a liquor circulation suction conduit communicating with said casing, said casing having a discharge opening at the bottom thereof.

5. A pulp digester having a discharge opening at the lower end thereof, a casing detachably secured to the bottom of the digester around the discharge opening, a screen in said casing and spaced from the walls thereof, and a liquor circulation suction con- 120 130

- duit communicating with said casing, said casing having a discharge opening at the bottom thereof.
6. A pulp digester having a discharge opening at the lower end thereof, a casing secured to the bottom of the digester around the discharge opening, a bottom plate secured to the lower end of said casing and having a central discharge opening therein, and a screen having a flange secured between said bottom plate and casing, said screen extending upwardly substantially throughout the length of the casing.
7. A pulp digester having a discharge opening at the lower end thereof, a casing secured to the bottom of the digester around the discharge opening, a bottom plate secured to the lower end of said casing and having a central discharge opening therein, a screen having a flange secured between said bottom plate and casing, said screen extending upwardly substantially throughout the length of the casing and being spaced from the casing wall.
8. A pulp digester having a discharge opening at the lower end thereof, a casing secured to the bottom of the digester around the discharge opening, a bottom plate secured to the lower end of said casing and having a central discharge opening therein, a substantially cylindrical screen having a flange secured between said bottom plate and casing, said screen extending upwardly substantially throughout the length of the casing.
9. A pulp digester having a discharge opening at the lower end thereof, a casing secured to the bottom of the digester around the discharge opening, a bottom plate secured to the lower end of said casing and having a central discharge opening therein, an open-ended screen having a flange secured between said bottom plate and casing, said screen extending upwardly substantially throughout the length of the casing.
10. A pulp digester having a discharge opening at the lower end thereof, a casing secured to the bottom of the digester around the discharge opening, a bottom plate secured to the lower end of said casing and having a central discharge opening therein, a substantially cylindrical, open-ended screen having a flange secured between said bottom plate and casing, said screen extending upwardly substantially throughout the length of the casing.
11. A pulp digester having a discharge opening at the lower end thereof, a casing secured to the bottom of the digester around the discharge opening, a bottom plate secured to the lower end of said casing and having a central discharge opening therein, a screen having a flange secured between said bottom plate and casing, said screen extending upwardly substantially throughout the length of the casing.
12. A pulp digester having a discharge opening at the lower end thereof, a casing secured to the bottom of the digester around the discharge opening, a downwardly sloping bottom plate secured to the lower end of said casing and having a central discharge opening therein, and a screen having a flange secured between said bottom plate and casing, said screen extending upwardly substantially throughout the length of the casing.
13. A pulp digester having a discharge opening at the lower end thereof, a casing comprising a cylindrical shell having a portion reduced in diameter and secured to the bottom of the digester around said opening, and a screen disposed in said shell, spaced from the major portion of the shell but substantially aligned with the reduced portion thereof.
14. A pulp digester having a discharge opening at the lower end thereof, a casing comprising a cylindrical shell having a portion reduced in diameter and secured to the bottom of the digester around said opening, and a substantially cylindrical screen disposed in said shell, spaced from the major portion of the shell but substantially aligned with the reduced portion thereof.
15. A pulp digester having a discharge opening at the lower end thereof, a casing comprising a cylindrical shell having a portion reduced in diameter and secured to the bottom of the digester around said opening, and a substantially cylindrical, open-ended screen disposed in said shell, spaced from the major portion of the shell but substantially aligned with the reduced portion thereof.
16. A pulp digester having a discharge opening at the lower end thereof, a casing comprising a cylindrical shell having a portion reduced in diameter and secured to the bottom of the digester around said opening, a screen disposed in said shell, spaced from the major portion of the shell but substantially aligned with the reduced portion thereof, and a bottom plate secured to said shell below said screen and having a central discharge opening therein.
17. A pulp digester having a discharge opening at the lower end thereof, a casing comprising a cylindrical shell having a portion reduced in diameter and secured to the bottom of the digester around said opening, a screen disposed in said shell, spaced from the major portion of the shell but substantially aligned with the reduced portion thereof, and a bottom plate secured to said shell below said screen and having a central discharge opening therein, said screen having

a flange secured to the bottom thereof and disposed between the lower end of the shell and said bottom plate.

18. A pulp digester having a discharge opening at the lower end thereof, a casing shell secured to the bottom of the digester and around the discharge opening thereof, a screen in said shell and spaced from the wall thereof, and a bottom plate secured to 10 said shell below said screen and having a central discharge opening therein.

19. A pulp digester having a discharge opening at the lower end thereof, a casing shell secured to the bottom of the digester 15 and around the discharge opening thereof, a screen in said shell and spaced from the wall thereof, and a bottom plate secured to said shell below said screen and having a

central discharge opening therein, said screen having a flange secured to the bottom 20 thereof and disposed between the lower end of the shell and said bottom plate.

20. A pulp digester having a discharge opening at the lower end thereof, a casing shell secured to the bottom of the digester 25 and around the discharge opening thereof, a screen in said shell and spaced from the wall thereof, a bottom plate secured to said shell below said screen and having a central discharge opening therein, and means 30 for conducting steam to the space between the screen and the casing.

In witness whereof, I have hereunto set my hand this 14th day of June, 1927.

ADOLPH W. WAERN.
